United States Patent Office

Des. 201,891
Patented Aug. 10, 1965

201,891

DART

Richard F. Hirsch, 1012 E. Acacia St., Apt. B,
Glendale, Calif.

Filed Feb. 8, 1965, Ser. No. 83,718

Term of patent 14 years

(Cl. D34—5)

FIG. 3

FIG. 2

FIG. 1

FIG. 1 is a side elevational view of a dart showing my new design;

FIG. 2 is a side elevational view shown at right angles to that illustrated in FIG. 1;

FIG. 3 is a plan view.

I claim:

The ornamental design for a dart, as shown.
